CLAIM

The ornamental design for an autonomy transportation vehicle with a liftable platform, as shown and described.

DESCRIPTION

1. Autonomy transportation vehicle with a liftable platform

1.1 : Bottom

1.2 : Perspective

1.3 : Front

1.4 : Left

1.5 : Perspective

1.6 : Back

1.7 : Right

1.8 : Top

1.9 : Left

1.10 : Front

1.11 : Perspective

1.12 : Perspective

1.13 : Bottom

1.14 : Back

1.15 : Right

1.16 : Top

The present application shows a new, original, and ornamental design for an autonomy transportation vehicle with a liftable platform; drawings shows two states: reproductions 1.1 to 1.8 show the state that the platform is embedded

(Continued)

within the vehicle body and reproductions 1.9 to 1.16 show the state that the platform is lifted out from the vehicle body.

1 Claim, 16 Drawing Sheets
